His Attorney.

UNITED STATES PATENT OFFICE.

CARL A. TORNEDEN, OF LINWOOD, KANSAS.

GATE OR DOOR LATCH.

1,322,272.

Specification of Letters Patent. Patented Nov. 18, 1919.

Application filed March 3, 1919. Serial No. 280,265.

To all whom it may concern:

Be it known that I, CARL A. TORNEDEN, a citizen of the United States, residing at Linwood, in the county of Leavenworth and 5 State of Kansas, have invented a certain new and useful Improvement in Gate or Door Latches, of which the following is a specification.

My invention relates to improvements in 10 gate or door latches.

One of the objects of my invention is to provide a gate or door latch adapted for being used on either a swinging or sliding gate or door.

15 A further object of my invention is to provide a gate or door latch which may be utilized for locking the gate or door in the closed or the opened position.

A further object of my invention is to 20 provide a gate or door latch which is simple in construction, which is cheap to manufacture, which may be readily applied to a gate or door by an unskilled person, which is durable and not liable to get out of order, 25 and which is easily operated and which is efficient in operation.

My invention provides still further novel means for locking the latch in the closed position.

30 My invention provides still further a latch which may be applied to a door which swings in either direction past the closed position.

My invention provides still further a 35 novel latch member and a novel bracket for engaging the latch member.

The novel features of my invention are hereinafter fully described and claimed.

In the accompanying drawing, which 40 illustrates the preferred embodiment of my invention.

Figure 1 is a perspective view of a gate or door of the swinging type provided with my improvement.

45 Fig. 2 is a horizontal sectional view of a gate or door, which may be either of the swinging or sliding type provided with my improved latch.

Fig. 3 is an elevation of what is shown 50 in Fig. 2.

Fig. 4 is a vertical sectional view on the line 4—4 of Fig. 2.

55 Fig. 5 is a vertical sectional view, showing the parts reversed and in the positions occupied by them when the latch member

is reversed in position as indicated in dotted lines in Figs. 2 and 3.

Fig. 6 is a horizontal sectional view, showing my improved latch applied to a door which may be either a sliding door or gate 60 or one which swings past the closed position in either direction.

Similar reference characters designate similar parts in the different views.

1 designates the door or gate which may 65 be a swinging door, as shown in Fig. 1 or which may be one of the slidable type. 2 designates the post or frame to which the door or gate is adapted to be locked in the closed position. 70

Referring first to Figs. 1 to 4, 3 designates the vertical portion of a bracket, which is adapted to be fastened to one side of the post 2 by means of screws 4 which extend through vertical slots 5, as shown in Figs. 75 1 and 3.

The bracket is provided with a horizontal portion 6, having on its upper side two spaced apart projections 7, which are also spaced apart from the rear or inner side of 80 the vertical portion 3. Each projection 7 inclines at its outer side in two directions at right angles to each other for the purpose hereinafter described.

8 designates a U-shaped latch member, the 85 arms of which near their outer ends are pivotally mounted upon a horizontal bolt 9, which extends through the gate or door 1 to which it is clamped by means of a nut 10, Fig. 2. 90

A spacing sleeve 11 extends on the bolt 9 through the arms of the latch member 8.

When the latch member is mounted on a door or gate as shown in Fig. 1, or in solid lines in Figs. 2 and 3, the transverse portion and one of the arms of the latch member 8 is adapted to releasably engage the projection 7 which is adjacent to the door or gate 1. By having the projection 7 thus engaged inclined on its outer side in two 100 directions at right angles to each other, the latch member 8 is adapted to be lifted by the projection in passing to the locking position shown in solid lines in Figs. 1, 2 and 3, when the latch member is pivoted on a door 105 or gate which either slides or swings.

For lifting the latch member 8 out of the locking position, from engagement with the projection 7 which it embraces, there is provided a finger member 12, which extends 110

through a transverse hole 13 in the door and through a transverse hole 14 in a right angled supporting member 15 which is fastened to the door or gate 1 on the same side 5 as the latch member 8. The finger member 12 is provided in one end with a notch 16 adapted to receive a horizontal pin 17 which pivotally supports the finger member and which is mounted in the outwardly extending 10 portion of the supporting member 15.

The finger member 12 at the opposite side of the pin 17 is provided with another notch 18, Fig. 4, adapted to receive the latch member 8. The finger member 12 extends under 15 the latch member 8 so that it may lift the latter out of engagement with the adjacent projection 7.

The outwardly extending portion of the supporting member 15 is provided with a 20 slot 19, through which the latch member 8 has one arm extending and which is adapted to receive a locking device, such as the hasp 20 of a padlock 21, as shown in Fig. 4. When the hasp 20 is inserted in the slot 19, 25 it engages the upper edge of the finger member 12 and holds it from being lifted.

The latch member 8 is adapted to be reversed to the position shown in dotted lines 30 in Figs. 2 and 3, when the door or gate is disposed at the other side of the post 2. With the latch member 8 so mounted in said reverse position, it is adapted to releasably 35 engage the other projection 7, in the manner already described with reference to the opposite projection 7. When the latch member 8 is in the reverse position shown in dotted lines in Figs. 2 and 3, the finger member 12 is reversed from the position shown in Fig. 4, to that shown in Fig. 5, this being 40 permitted by reason of the fact that the notch 16 in the end of the finger member 12 permits of the withdrawal of the latter from engagement with the pin 17, which it pivotally engages. Such disengagement of the 45 finger member 12 from the pin 17 may be effected by removing the bolt 9 and withdrawing the latch member 8 from the supporting member 15.

When the latch is mounted on a swinging 50 gate or door as shown in Fig. 1, it may be locked in the open position by means of another bracket 3 attached to the wall 22 to which the door or gate is hinged, as shown in Fig. 1. This second bracket 3 is the same 55 in construction as the one already described, being provided with the horizontal portion 6 having two spaced apart projections 7 inclined on their outer sides in the manner already described with reference to the other 60 projections 7. When the gate or door 1 is swung to the fully opened position, the outer arm and the transverse portion of the U-shaped latch member is adapted to releasably 65 engage the projection 7 of the bracket 3 which is attached to the wall 22, said pro-

jection being the one nearest to the gate or door 1.

When the latch is to be used on a door which swings past the closed position in both directions, a bracket corresponding in construction to the brackets 3 is mounted on the post 2 at the side next adjacent to the door or gate 1, as shown in Fig. 6. When applied to such a gate or door, if desired, the latch member may be disposed with its arms 70 at opposite sides respectively of the gate or door 1, as shown in Fig. 6. In such arrangement, the spacing sleeve 11 is extended through the gate or door 1, and the supporting member 15 is spaced apart from the 80 door or gate 1 by a spacing sleeve 23, and is attached to the door at the side opposite to the side to which it is attached in Fig. 2.

By lifting the latch member 8, either by grasping its arms or by means of the finger 85 member 12, the latch member may be lifted clear of the projections 7, so that the door or gate 1 may be swung in either direction or slid to the open position, depending upon the type of door employed. Upon closing 90 the door, the latch member 8 will automatically engage with the projections 7, the inclination of the outer sides of said projections permitting the latch member to be automatically lifted in moving to the locking 95 position when the door is either slid or swung to the closed position.

The slots 5 in the brackets 3 permit of the vertical adjustment of said brackets in case the door sags or in the initial instalment of 100 the mechanism.

I do not limit my invention to the structure shown and described, as modifications, within the scope of the appended claims may be made without departing from the 105 spirit of my invention.

What I claim is:—

1. In a gate or door latch, a bracket having on its upper side a projection the outer side of which inclines at right angles in two 110 directions, and a latch member adapted to be pivoted to a door or gate and provided at its free end with a transverse arm, the projection being adapted to be embraced in the angle made by the arm with the body of the 115 latch member.

2. In a gate or door latch, a bracket having on its upper side two projections which are spaced apart from each other, each projection on its outer side inclining in two 120 directions at right angles to each other, and a latch member adapted to be pivoted to a door or gate and provided at its free end with a transverse arm adapted to pass between said projections, when said latch 125 member is pivoted at either side of said bracket.

3. In a gate or door latch, a bracket having on its upper side two spaced apart projections, each inclining on its outer side in 130

- two directions at right angles to each other, and a U-shaped latch member adapted to be pivoted to a door or gate and to be reversed in position so as to have one of its 5 arms and its transverse portion engage one of said projections when in one position and to have the other arm and its transverse portion engage the other projection when in the reverse position.
- 10 4. In a gate or door latch, a bracket having on its upper side an inclined projection, a finger member having two notches, a support adapted to be fastened to a door or gate provided with a pin adapted to be 15 mounted in one of said notches, and a reversible latch member adapted to be pivoted to the gate or door and to releasably embrace said projection and located in the other notch of the finger member, the latter being adapted for being reversed in position on the pin and latch member.
- 20 5. In a gate or door latch, a bracket having on its upper side an inclined projection, a support adapted to be fastened to a door or gate and provided with a hole and 25 a pin, a latch member extending through said hole and adapted to releasably engage said projection and to be pivoted to the door or gate, a finger member pivoted to said pin and extending below and adapted to lift 30 the latch member, and a locking device adapted to be extended through said hole and to engage the finger member for holding it from being lifted.
6. In a gate or door latch, a bracket having on its upper side an inclined projection, a support adapted to be fastened to a door or gate and provided with a hole, a latch member extending through said hole and adapted to releasably engage said projection and to be pivoted to the door or gate, a finger member pivoted to said support and extending below and adapted to lift 35 the latch member, and a padlock having its hasp adapted to releasably engage said support and said finger member for holding the latter from being lifted.

In testimony whereof I have signed my name to this specification.

CARL A. TORNESEN.
